UNITED STATES PATENT OFFICE.

SAMUEL S. FRETZ, OF PHILADELPHIA, PENNSYLVANIA.

GEAT FOR UMBRELLAS.

SPECIFICATION forming part of Letters Patent No. 691,053, dated January 14, 1902.

Application filed May 13, 1901. Serial No. 59,962. (No model.)

To all whom it may concern:

Be it known that I, SAMUEL S. FRETZ, a citizen of the United States, residing at Philadelphia, in the county of Philadelphia and 5 State of Pennsylvania, have invented new and useful Improvements in Hinges for Umbrella Ribs and Stretchers, of which the following is a specification.

My invention relates to the hinge between 10 the rib and stretcher of umbrella-frames.

It has for objects providing a better side bearing than has heretofore been possible to the stretcher, forming a closer fit than has hitherto been attained between the bearing- 15 surfaces at the side of the stretcher and the bearing part on the inside of the groove of the rib, and thus making a more rigid frame, and at the same time by avoiding piercing the rib on more than one side to make the rib 20 stronger at the point of junction with the stretcher than in former structures.

The objects are attained by the device below described.

Figure 1 is a plan view of the rib and 25 stretcher on an enlarged scale. Fig. 2 is a cross-section on line $x-x$ of Fig. 1. Fig. 3 is a similar cross-section of a modification.

The rib A is the ordinary paragon-rib. Around this rib is the lap B. It passes around 30 the outside of the rib, and the ends 2 2 are folded into the inside of the groove of the rib A, forming a flat bearing-surface on either side of the portion of the stretcher inserted between them. These portions 2 of the lap 35 are supported firmly by the side walls 3 3 of the rib, but, however, with an elastic support, allowing them to yield slightly under a severe twist and go back again into position by the springing of the highly-elastic material forming the walls 3 3 of the rib. Between the inside surfaces of the ends 2 2 is inserted the flattened end 4 of the stretcher. This end is 40 preferably large enough and so shaped that it will be slightly elastically clamped by the side walls of the rib and will provide a fairly 45 extensive side bearing-surface in contact with the inside of the ends 2 2 of the lap.

Now it will readily be seen that if a rivet 50 passes through both of the side walls 3 3 of the rib A and is secured to them in the usual manner these walls cannot spread, and if the rivet is tightly put in, as it should be,

they are fixed at a constant distance from each other and all power of elastic support for the lap, and consequently of elastic bearing for the stretcher, prevented. Hence the hinge where the rivet passes through both side walls of the rib is absolutely unyielding, and in case of a sudden strain the frame is 55 permanently twisted. I obviate this by my 60 construction. I penetrate one side wall 3 of the rib A with the hole 6, making the holes 5 and 7 in the portions of the lap folded around that part of the rib registering with the hole 6. Through the holes 5, 6, and 7 is inserted 65 the pin D, which also passes through the end of the stretcher and through a hole 8 in the end 2 of the lap folded inside of the side wall of the rib opposite the one pierced with the hole 6 and is abutted against this wall. The end 70 of the pin D is enlarged—in practice this being done by the abutting—and thus secured to the end 2 of the lap. I generally make this hole in the end of the lap larger than the hole 75 in the stretcher and cause the enlargement of the end of the pin to lie principally within this hole and the pin to be held in place by the end being jammed against the sides of the hole 8, the enlarged end thus forming a 80 collar to aid in preventing the end of the stretcher from moving along the pin.

It will be seen from the above description that the two opposite walls of the rib are not in any way bound to each other and are free to yield slightly upon a severe strain. By 85 reason of this the stretcher can be fitted much more closely than hitherto had dared to be done when a strain would, unless there was sufficient lost motion to allow it to have some play, cause a permanent bending of some 90 part. This is especially the case in stretchers of the variety where the end of the stretcher is inserted into the rib-groove and has to be strengthened by a rigid piece of material inserted in the end. In the case of 95 this invention, on the other hand, since the lap will readily yield, the stretcher will simply slightly shift the lap to which it is secured, and the walls of the rib will yield slightly and will spring back, pushing back the lap 100 into its original position when the strain is removed. In addition to this the piercing of only one wall does not weaken the intact wall, and the rib remains stronger, especially on

the side which under my construction is not as much strengthened by the lap as the other.

In Fig. 3 is shown a form of my device where the pin D' is abutted against the inside 5 of end 12 of the lap B' instead of against the inside of the side wall of the rib A' and is provided with a slight collar 15, if necessary, outside the end of the stretcher C'.

Having now described my invention, what 10 I claim, and desire to secure by Letters Patent, is—

1. The combination of a paragon-rib; a lap surrounding said rib, and having its ends lying inside of and against the inside of the 15 side walls of the rib; a flat end stretcher, having the flat end inserted between the ends of the lap and fitting against the same; and a pin penetrating one side wall only of the rib and through the lap and the stretcher, 20 whereby the side walls of the rib are left free to spring toward and away from each other; substantially as described.

2. The combination of a paragon-rib; a lap surrounding said rib and having its ends lying inside of and against the inside of the 25 side walls of the rib; a flat end stretcher, having the flat end inserted between the ends of the lap, one of the side walls of the rib and the portions of the lap lying at either side of it being provided with holes, and the end of 30 the lap lying opposite thereto having a hole therein somewhat larger in diameter than the hole through the stretcher; and a pin passing through these holes and having an enlarged end fitting the enlarged hole in the 35 last-named end of the lap; substantially as described.

In testimony whereof I affix my signature in presence of two witnesses.

SAMUEL S. FRETZ.
